UNITED STATES PATENT OFFICE.

FRANK JAGER, OF CHICAGO, ILLINOIS.

CAR-LADDER.

1,376,696.

Specification of Letters Patent.

Patented May 3, 1921.

Application filed July 9, 1919. Serial No. 309,577.

To all whom it may concern:

Be it known that I, FRANK JAGER, residing in Chicago, in the county of Cook and State of Illinois, have invented certain new and useful Improvements in Car-Ladders, of which the following is a full, clear, and exact description, reference being had to the accompanying drawings, forming a part of this specification.

10 My present invention relates in general to ladders, and has reference, more particularly, to ladders of the type designed for use in connection with railway box cars and the like, one object being to simplify and facilitate the construction of ladders of this type to reduce the element of cost to the minimum. Another object of the invention resides in the provision of a ladder of this character which may be very easily assembled and quickly applied to the car by the most unskilled laborer, thus effecting a material reduction of labor cost in this direction.

15

A further object of the invention involves the utilization of standard or commercial iron elements as component parts of the ladder, and wherein all such ladder parts are rigidly maintained in a locked relation without the necessity for bending rung ends or riveting stiles to supporting brackets, though the parts may be very readily disassembled for the purpose of repair or replacement.

20 A still further advantage of the invention results from the employment of standard or stock sizes of parts throughout the ladder thereby permitting repair of the same in any repair shop regardless of whatever class of labor is there available.

25 The invention still further contemplates the provision of novel details of construction, combination and arrangement of the parts of the ladder whereby the end rungs of the ladder may co-act directly with the ladder brackets in the interest of economy in labor and material, and of ease in assemblage and application to the car siding and at the same time to attain the utmost degree of rigidity in the mounting of the ladder.

30 These, together with such other objects and advantages as may be hereinafter described, or are incident to my invention, I attain by means of a construction illustrated in preferred form in the accompanying drawing, 35 wherein:

Figure 1 represents a side elevation of a

portion of a car siding to which my improved ladder is shown applied:

Fig. 2 is an enlarged cross-sectional view illustrating the assembled relation of the 60 ladder parts:

Fig. 3 is a view in transverse section taken through Fig. 1 along the line 3—3:

Fig. 4 is a similar view, but illustrating the method of assembling and disassembling 65 the parts of the ladder:

Fig. 5 is an enlarged section illustrating the means for attaching a ladder to the car: and,

Fig. 6 is a similar view illustrating a 70 modified form of ladder mounting.

Referring more particularly to Fig. 1 of the drawing, it will be seen that the reference character A denotes the car siding of the car to which the ladder, comprising angle 75 bar stiles B and rungs C is applied by means of end brackets D, and central brackets E. Heretofore, in ladder constructions, it has been proposed to form the end of each rung with a reversed bend so that in assembling 80 the ladder parts such bent end may be engaged in holes found in both flanges of the angle bar stile, in which case also, the supporting bracket was, and necessarily so, to be riveted directly to the stile.

85 This bending, however, required at least two heats for each end of the rung, hence in a ladder employing a series of rungs this treatment alone added materially to its cost. This item was furthermore increased in view 90 of the bracket riveting requirement, and obviously so since ladders are most frequently shipped in a knocked-down condition for later assemblage and application to the car at destination, where riveters and riveting 95 equipment had to be maintained.

95 My invention has for its principal aim to produce a relatively cheaper ladder in which these stated processes have no part either in the making or in the assemblage of its parts, 100 and wherein the latter may be readily brought into a thoroughly locked organization, while in the event of damage occurring to any of its parts, such may be repaired in a facile manner by a class of labor not ordinarily employed in these processes.

105 In carrying out my invention, the angle bar stiles B are each arranged so as to have one of their divergent wall portions or flanges 7 extended inwardly toward the siding, and these flanges are formed with rung receiving apertures 6 located in close prox-

imity with the other flanges 8 which are extended in a direction outwardly away from these said apertures. The rungs there, as shown, comprise in each instance an ordinary stock bolt headed at one end and threaded at the other, the head, preferably of rectangular cross-section, being designated by the reference numeral 9 and the threaded end is indicated by the numeral 10.

10 Prior to the application of the stiles to the siding by means of the brackets D, each of the rung bolt members therein is first inserted endwise through a hole in one of the flanges 7, and then continued endwise 15 through a hole in the other flange 7 until the threaded end 10 extends well beyond the last mentioned flange in order to receive the nut 11, as will be readily understood by a reference to Fig. 4 of the drawings. In this 20 figure the left hand stile is, as already indicated, moved somewhat to the right in order to permit engagement of the nut 11 with the threaded end 10 of each of the rungs. After each of the nuts 11 have been 25 advanced a predetermined distance upon the threaded ends of the rungs, the left hand stile is then moved to the left until flange 7 abuts against the inner face of each of the nuts 11. At the same time, the outwardly 30 extending flange of the right hand stile abuts the outer face of the head 9 in such a manner as to lock the rung against rotation, and the similar flange on the left hand stile also has an abutting relation with the outer face of 35 the nut 11 which serves to prevent any involuntary uncoupling of said nut. Obviously, in the disassemblage of any of the above mentioned parts, all that is required to be done is to move one or the other of the 40 stiles sufficiently inwardly so as to permit the uncoupling of the nut from the rung bolt member. In other words, I aim to utilize as stiles a pair of angle bar members, together with a series of headed bolt members, serv- 45 ing as rungs, together with their comple- mentary nuts, all being so organized as to permit their ready assemblage and applica- 50 tion to the car by the most unskilled class of labor. When applied, the rungs are locked against rotation, while the only removable 55 elements, the nuts, are prevented from back- ing off the rungs. The parts of the ladder are such as to make for ready repair, or re- placement, at any car shop.

55 Referring now more particularly to Figs. 3 and 6 of the drawings, wherein my preferred form of mounting for the ladder is disclosed, it will be seen that the bracket D has its outwardly extending flange 12 pro- 60 vided with an aperture 13 corresponding to the rung hole in the flange 7 with which it is intended to coöperate. This flange 12 is continued beyond the hole 13 to engage the flange 8 in the vicinity of the apex of the 65 stile. These brackets may be employed in

connection with the upper and lower rungs, while at the same time the flanges 12 of the brackets E press against the inner faces of the stiles. When assembling the parts, these rungs in passing through the rung holes in 70 the stiles are also passed through the rung holes 13 of the bracket flanges 12, whereupon the end nuts 11 are coupled on the threaded ends of the rungs. Before the stile or stiles are moved along the rung to the 75 position indicated in these figures, the brackets are themselves held in a rigid locked relation, and being carried on the rung ends themselves the necessity for riveting the brackets is obviated, and as a resultant 80 thereof, a simple and cheap construction is produced. In order to attach the brackets D and E to the siding A, bolts 14 extend through the inner flanges 15 of the brackets and hence through the siding for the recep- 85 tion of the inner securing nuts 16. In this way, the number of apertures in the car siding is reduced to the minimum. If desired, the inner flanges of the stiles may be con- 90 tinued or extended inwardly until they abut the bracket flange 15 near the apex of the bracket, as shown in Fig. 6, and the bolt 14 may be provided with a squared head 14', one side face of which may abut an inner 95 face portion of the stile flange 7 in a lock- 100 ing relation therewith. Furthermore, as indicated in said Fig. 6, the stile flange 8 may be formed with a marginal rib 17, formed and located so that a slight tilting of the rung will permit the passage of the nut 11 during the assembling of the ladder parts, whereupon when the stiles are positioned 105 against the siding by the brackets, inward movement of the stiles along the rungs, under abnormal impact from external causes, 110 is prevented, and the integrity of the ladder maintained. Other advantages of the invention will be apparent to those skilled in the art.

I do not intend to be understood as limit- 110 ing myself to the precise details of construction and arrangement of the parts as shown, as it will be manifest that modifications thereof may be made in the adaptation of the ladder to various conditions of use with- 115 out departing from the spirit and scope of my invention and improvements. For ex- ample, the laterally extended stile flanges may be so positioned as to engage the inner 120 faces of the heads and nuts, instead of their outer faces, and obviously the angle bar stiles may be made of wood, if desired; I, therefore, reserve the right to all such and other modifications as properly fall within the scope of the invention and the terms of 125 the following claims.

I claim:

1. In a ladder, the combination of a pair of angle bar stiles comprising divergent flanges, one of said flanges formed with 130

- a plurality of rung receiving holes and the other with an abutment near each of said holes but spaced laterally and outwardly therefrom, rungs having their end portions 5 engaging said holes, and rung securing elements on said end portions positioned within the abutments whereby each element engages both flanges of the stile with which it coöperates.
- 10 2. In a ladder, the combination of a pair of angle bar stiles each having the inwardly extending flange thereof provided with rung receiving holes, angle bar supporting brackets each having one flange adapted 15 to be bolted to the side of a car, and the other flange extending outwardly from the face of the car and provided with a rung receiving opening adapted to be alined with one of the rung receiving openings of said stiles, a rung bolt extending through the 20 openings in said stile flanges and in said bracket flanges, and a nut threaded on the outer end of said bolt, the outer flanges of said stiles being so disposed with respect to the rung receiving openings that said nut 25 and the head of said rung bolt are engaged by said flanges respectively when the stiles are adjacent the ends of the bolts, whereby said bolts and nuts are held against accidental rotative movement.

FRANK JAGER.
